The Schedule referred to in these Letters Patent and making part of the same

To all to whom these presents shall come

Be it known that we, J. Cox, Elias Johnson, D. B. Cox of Troy in the County of Rensselaer and State of New York have invented or produced a new and original design for cooking Stoves and that the following is a full, clear and exact description of the principle or character which distinguishes it from all other things before known reference being had to the accompanying drawing, making a part thereof.

This design consists in a peculiarly constructed set of ornamental figure work comprising and ornamental pattern. Fig 1. is a front of the stove. The top part bears a tablet with a legend below which are the double doors. In the upper part of these doors there are openings with slide valves to close them and below these is the ornamental pattern or design composed in part of flat ribbons or bands wrought into a pattern the center of which is a harp in form, at the lower part of which is a cross and a border formed with the outer portions of the scroll work. The hinges are of an angular pattern beaded heavily on each edge, and the whole pattern presents an angular figure interspersed with curves clearly shown by the drawings. The side is finished with a small fire door in the upper front corner, and the pattern thereon is similar to that on the front doors but in this there is a circle in the centre of the pattern instead of the harp, the side door is an oblong parallelogram with its upper front corner abbreviated forming a trapezium with three right angles. The ornaments upon this door like the others are composed of flat ribbons wrought into pattern the outer having a moulding superadded to the ornaments of the other parts. Along the top and bottom of the side plate above and below the oven door is an ornamental border in the same style the lower border extending forward to a panel at the forward end of the side plate.

2

Dec 382

and the upper ^{one} to the fire door, the two ends of the side plate have two long narrow panels extending from top to bottom, a diamond figure fills the space under the fire door.

Having thus fully described our ornamental designs what we claim and desire to secure by letters patent is the ornamental design shown pattern above described formed of flat ribbons as fully illustrated
